UNITED STATES PATENT OFFICE.

LESLIE H. BURLIN, OF CHICAGO, ILLINOIS, ASSIGNOR TO BURLIN CO., A FIRM COMPOSED OF LESLIE H. BURLIN AND WALTER H. SEDGWICK, OF CHICAGO, ILLINOIS.

LAMP SHADE.

Application filed June 19, 1924. Serial No. 720,991.

To all whom it may concern:

Be it known that I, LESLIE H. BURLIN, a citizen of the United States of America, and a resident of Chicago, in the county of Cook 5 and State of Illinois, have invented certain new and useful Improvements in Lamp Shades, of which the following is a specification.

This invention relates to that class of 10 lamp shades in which the main ornamental portion is formed of a pliable material such as silk or like woven fabric and is attached to and supported by a rigid under frame of metal or the like. And the present improvement has for its various objects:—

To provide a structural formation and combination of parts and features, whereby a substantial attachment between the pliable main portion and the rigid supporting ring or rings of a lamp shade is attained in a rapid and economical manner.

To provide a combination of parts in the sectional rigid supporting frame or rings 25 of a lamp shade, whereby a tensioning of the pliable and ornamental portion of the shade is attained in a ready and substantial manner.

To provide a formation and combination 30 of parts whereby the pliable ornamental lining of the rigid skeleton crown member of the supporting frame is attached thereto in a substantial and convenient manner, all as will hereinafter more fully appear.

35 In the accompanying drawings:

Fig. 1, is a plan view of a lamp shade to which the preferred form of the invention is applied.

Fig. 2, is a side elevation, with parts of 40 the superimposed layers of fabric, etc., broken away and removed to disclose underlying parts.

Fig. 3, is an enlarged fragmentary section of the completed shade.

45 Fig. 4, is a fragmentary section of the upper and lower rigid members or rings of the supporting frame, and showing the means for effecting an adjustment between the same.

50 Fig. 5, is a detail elevation of a portion of the lower ring member of the supporting frame.

Like reference numerals indicate like parts in the several views.

55 As shown in the drawings, the rigid sup-

porting frame or member of the lamp shade, preferably comprises a lower annular ring 1 of a circular, elliptical or other usual shape, and an upper annular ring 2 of a corresponding shape, and which is preferably connected by an intermediate skeleton web 3 with a central attaching collar or hub 4 hereinafter described. The intermediate web 3 being preferably of a dome shape as shown.

In the present improvement the frame rings 1 and 2 are provided with peripheral holding grooves or channels 5, and in the preferred construction such grooves 5 are formed by spaced rows of lugs 6, arranged in staggered relation on the periphery of the rings, as shown more particularly in Figs. 2 and 5, with a view to the ready molding of the same when made by casting.

The connecting means between the frame rings 1 and 2 is of the expanding type in order to attain the hereinafter described tensioning of the pliable lamp shade member, and preferably comprises a plurality of stay rods 7, the upper ends of which rest in sockets formed therefor in the under surface of the upper frame ring 2, while the lower ends of said stay rods rest upon adjusting screw plugs 8 having adjustment 75 in a plurality of screw-threaded orifices in the lower frame ring 1, as illustrated more particularly in Fig. 4.

An ornamental lining 9 of fabric or like pliable material is arranged inside the crown shaped skeleton web 3 of the upper frame member 2 and is visible through the open ornamental formation of said web. At its center the lining 9 is formed with a circular orifice for the passage of the shank 80 of the electric light bulb used in connection with the lamp shade, and in the present construction such orifice is reinforced by a rigid ring or annulus 10 attached to the lining and to the hub portion of the upper frame ring 2 by attaching screws or rivets 95 11.

At its outer margin or border, the lining 9 is folded over the periphery of the upper frame ring 2 and is secured thereto by a winding 12 of thread or the like, such winding being adapted to force the material of the lining 9 into the above described peripheral groove 5 of the upper frame ring 2 and effect a firm and substantial attachment of parts.

The main body or portion of the lamp 110

shade is formed of pliable material, preferably a plurality of layers 13 of silk or like fabric, arranged to surround the frame rings 1 and 2 and extending between said rings to 5 constitute the translucent wall of the lamp shade, with the upper and lower margins thereof secured to the respective frame rings 1, 2, in manner similar to that above described in connection with the crown 10 lining 9, that is to say, the respective margins of each layer 13 of fabric, commencing with the innermost layer as secured in place in the peripheral channels 5 of the frame rings 1 and 2 by individual windings 14 15 of thread or the like, with the innermost layer of fabric laying outside the lining 9 and its individual winding 12, and with each succeeding layer of fabric and its individual windings 14 overlaying the preceding layer of fabric, as illustrated more 20 particularly in Figs. 2 and 3. In the preferred method of operation, the last and outermost winding 14' of thread will be saturated with a liquid adhesion, either during 25 the winding operation or subsequent thereto, with a view to obtain a binding together of the individual threads of the winding, and thus prevent accidental unwinding of the winding 14' after assembly 30 and during actual use of the shade.

In my preferred construction shown, the adhesive properties imparted to the aforesaid outer winding 14' is employed to secure in place upper and lower ornamental 35 bands or braids 15 and 15' applied over the windings 14', so as to cover same and add to the ornamental finish of the lamp shade. In the successive application of the plurality of layers 13 of fabric, any desired 40 pleated or other usual ornamental formation may be imparted to each layer as it is laid in place on the frame rings 1 and 2 aforesaid.

The central collar or hub 4 of the upper 45 frame ring 2 is preferably of an ornamental scalloped form as shown, and is provided at one side with a radially arranged attaching screw 16, and in opposed relation to such screw, and within the orifice of the 50 collar, with a pair of inwardly projecting lugs 17. With such construction a simple and substantial connection between the lamp shade and the lamp socket of the lamp stand or bracket can be readily made by an 55 engagement of the screws 16 and lugs 17 behind the usual peripheral bead on said lamp socket.

Having thus fully described my invention, 60 what I claim and desire to secure by Letters Patent is:—

1 In a lamp shade of the type described, 65 the combination of a frame ring provided with spaced rows of lugs in staggered relation on its periphery to form a holding groove therein, a shade member of pliable

material, and a winding of thread for securing a margin of the pliable material in said groove

2. In a lamp shade of the type described, 70 the combination of upper and lower frame rings arranged in spaced relation and formed with holding grooves in their outer surfaces, a shade member of pliable material, windings of thread for securing opposite margins of said pliable member in said holding grooves, and an extensible member 75 arranged intermediate of said rings for effecting a spreading apart of the same and tensioning of the aforesaid pliable member.

3. In a lamp shade of the type described, 80 the combination of upper and lower frame rings arranged in spaced relation and formed with holding grooves in their outer surfaces, a shade member of pliable material, windings of thread for securing opposite 85 margins of said pliable member in said holding grooves, and means for spreading said rings apart, the same comprising a plurality of intermediate rods, one end of each of which has bearing in a socket in one 90 frame ring, and an adjusting screw arranged in the other of the frame rings and forming an abutment for the other end of the aforesaid rod.

4. In a lamp shade of the type described, 95 the combination of upper and lower frame rings arranged in spaced relation and formed with holding grooves in their outer surfaces, a shade member formed by a plurality of layers of fabric, individual windings of 100 thread for securing opposite margins of said layers in the aforesaid holding grooves, and means for spreading said rings apart to tension said layers of fabric.

5. In a lamp shade of the type described 105 the combination of a rigid frame member formed with a border ring, a central attaching collar and a skeleton web of a dome shape connecting the ring and collar together, the border ring having a holding 110 groove in its outer surface, a lining of pliable material arranged beneath said connecting web, and having its margin secured in said holding groove, a shade member of pliable material the upper margin of which 115 is also secured in said holding groove outside the marginal portion of the aforesaid lining, with the marginal portions of the shade member and lining covering and concealing the perimeter of the border ring 120 aforesaid.

6. In a lamp shade of the type described, 125 the combination of an upper rigid frame member formed with a border ring and a central attaching collar connected to said border ring by a skeleton web of a dome form, a lower rigid frame member of a ring form arranged in spaced relation to the upper frame member, said rings having holding grooves in their outer surfaces, a lining 130

of pliable material arranged beneath the aforesaid connecting web, and having its margin secured in the holding groove of the upper frame member by a winding of 5 thread, a shade member of pliable material, windings of thread for securing opposite margins of said shade member in the holding grooves, and means for spreading said frames apart to tension said pliable shade 10 member.

7. In a lamp shade of the type described, the combination of an upper rigid frame member formed with a border ring and a central attaching collar connected to said 15 border ring by a skeleton web of a dome form, a lower rigid frame member of a ring

form arranged in spaced relation to the upper frame member, said rings having holding grooves in their outer surfaces, a lining of pliable material arranged beneath 20 the aforesaid connecting web, and having its margin secured in the holding groove of the upper frame member by a winding of thread, a shade member formed by a plurality of layers of fabric, individual windings of thread for securing opposite margins of said layers in the aforesaid holding grooves, and means for spreading said frames apart to tension said layers of fabric. 25

Signed at Chicago, Illinois, this 12th day 30 of June, 1924.

LESLIE H. BURLIN.
